ALFRED C. BEDORTHA AND GEORGE Q. BEDORTHA, OF WINDSOR,
CONNECTICUT.

TREATMENT OF TOBACCO.

NO. 821,919.

Specification of Letters Patent.

Patented May 29, 1906.

Application filed April 19, 1900. Serial No. 13,452.

To all whom it may concern:

Be it known that we, ALFRED C. BEDORTHA and GEORGE Q. BEDORTHA, citizens of the United States, and residents of Windsor, in the county of Hartford, State of Connecticut, have invented certain new and useful Improvements in the Treatment of Tobacco, of which the following is a full and true description, reference being had to the accompanying drawings, showing a form of apparatus useful in carrying out our new process.

The object of our invention is to treat tobacco of an inferior or less esteemed flavor so as to give it another and more desirable flavor, thereby enhancing its commercial value.

Our invention is particularly applied to the treatment of tobacco comprising, first, sterilizing the tobacco under such conditions and sufficiently long-continued as to destroy the original bacteria and spores existing thereon, then adding to the sterilized tobacco bacteria or cultures thereof to produce a new and characteristic flavor, and subsequently subjecting the tobacco to fermentation.

The present invention is based upon the discovery that the sterilization of the tobacco may be effected by subjecting it to the action of hot air and that there are certain advantages secured by practicing the hot-air process, notably in the treatment of tobacco to be used as cigar-wrappers.

We have also devised novel apparatus for subjecting tobacco to the sterilizing action of hot air.

In carrying out our invention we first subject the tobacco to the action of hot air, whereby it is thoroughly sterilized and the bacteria and "spores" existing thereon are destroyed, and before subjecting the said tobacco to a "fermenting" or "ripening" process we add thereto bacteria or cultures thereof of the kind existing or developed upon the higher grade tobacco at the plantations. The tobacco is then piled and set aside in well-known ways for the purpose of allowing the leaves to ferment or "sweat" or "ripen."

In the accompanying drawings we have illustrated a form of apparatus useful in treating tobacco according to our process.

Figure 1 illustrates a horizontal longitudinal section of one form of apparatus for carrying out our new process, and Fig. 2 illustrates a vertical longitudinal section of the said apparatus.

As illustrated, the sterilizer has an inner casing B and an outer casing C, each permanently closed at its rear end by concaved plates D E, respectively. The casings B and C and end plates D and E are separated from each other by a space constituting a steam-jacket F.

G is an annular plate at the front of the sterilizer, adapted to support the door H hinged thereto, as well as to have either the said door H or a second door or cover Y, hereinafter described, bolted thereto.

J and K indicate pipes connected with any suitable source of supply for delivering steam to the steam-jacket F.

The door H is hinged to the end ring G of the sterilizer. Said end ring is provided with bolts R, hinged thereto and having their outer threaded ends provided with clamping-nuts, so as to swing outwardly when the cover Y is removed. The door H is provided with radial edge slots Q, in which the bolts R fit when the door is shut, the door being then tightly locked by screwing the clamping-nuts.

A second door, Y, preferably made of thick heavy planking or of wood and metal, may be fitted to or removed from the open end of the sterilizer when the first-named door H is swung to an open position. The door Y is provided with radial edge slots in positions, and preferably in size and number also, corresponding to the slots Q in the hinged door H. The removable door Y has two openings through it, one being at or near the center for admitting a pipe I P, which extends a considerable distance into the sterilizer, and a second, opening near to the edge of the door, for admitting a pipe E P, the said pipes I P and E P fitting the said openings tightly, but removably.

Within the sterilizer are tracks T, which are of assistance when a car or truck U is employed to bring the tobacco under treatment into or out of the sterilizer.

The pipes I P and E P are connected to the incoming and outgoing ports of an air heating and circulating device comprising a heater H', containing steam-heated pipes, and a connected rotary blower or fan F'. A second heater Z is connected by a pipe Z' with a pump or other device for forcing air through the heater. A pipe Z² connects the heater with the interior of the sterilizer. The heater is heated by steam-pipes S',

In practicing our new process for treating tobacco we prefer to first thoroughly dry the tobacco, care being taken to drive off all moisture contained within the leaves without, 5 however, subjecting them to a treatment which might destroy their texture or quality. The drying may be effected outside of the sterilizer by the usual evaporation, for instance. The thoroughly-dried tobacco is 10 loosely supported with the leaves, separated to permit a circulation of hot air between them. In order to quickly and easily accomplish this, we employ a number of racks W, piled upon a wheeled car U, the tobacco being placed between the racks. The car U, 15 which travels upon the tracks T, is then pushed into the sterilizer, and the door Y is bolted in place, completely closing the entrance to the sterilizer. The pipes I P and 20 E P are then fitted through said door and the circulating-fan F' is started. This causes air to be drawn from the sterilizer through pipe E P, sucked through the heater H', (where it becomes heated,) and the fan then 25 forces the heated air through the pipe I P into the sterilizer in such a position as to strike the racks on the car and to circulate between said racks and between the leaves of the tobacco placed thereon. After passing 30 through the racks the hot air returns along the sides, bottom, and top of the sterilizer to the pipe E P, again passing into the heater. The circulation and reheating of the air is continued until the air has reached 35 a temperature (say 250° Fahrenheit) sufficiently high to destroy the bacteria and spores existing on the tobacco. We do not desire, however, to be understood as confining ourselves to the employment of any certain 40 temperature, nor do we desire to be understood as declaring it to be essential that all bacteria and spores shall be killed by subjecting them to the action of the circulating hot air. It is obvious that as long as the tobacco is freed by the employment of hot air 45 from the original bacterial growth it is immaterial, for the purposes of our invention, how that is done.

It is desirable to thoroughly dry the tobacco before sterilizing it. Otherwise the 50 hot air tends to cause the moisture of the leaves to be converted into steam, which boils on and in the leaves, thus causing an effect which is similar to that produced by boiling the tobacco in water. This unless guarded against would result in injury to the 55 quality and structure of the leaves. This step in drying the leaves is not that employed in the curing of the tobacco, but is 60 a subsequent operation. The tobacco after curing has to become moist in order to be handled in the sheds without breaking and is ordinarily kept so for the fermenting process. The drying step employed by us makes 65 possible the application of heat as a steril-

izing agent without injury to the leaves and shortens the time by allowing the air to penetrate between the leaves and between the folds of the leaves, which it would not do if the leaves were moist and flexible. It is to 70 be understood that when we speak of "drying" tobacco we mean a drying which will correspond to air-drying or kiln-drying, which is usually carried out at less than 150° Fahrenheit, and not a drying to render the 75 tobacco "water-free," as the term is used in chemical analysis and which is usually effected at about 212° Fahrenheit. This drying renders bacteria very resistant to sterilizing influences, and especially to destruction 80 by heat. While active bacteria, notably certain pathogenic germs and the lactic-acid bacteria, are killed by the use of a temperature of 160° Fahrenheit from ten to fifteen minutes, it must be remembered that the dry 85 and more resistant spores, which spores is the condition of the tobacco bacteria after drying, require a far greater heat and longer continued than do the active bacteria themselves. In our practice we have found that 90 at least 250° Fahrenheit, lasting for thirty minutes, is necessary to destroy these spores.

We find that generally there are small "pockets" of air between some of the leaves which are being treated by the circulation of 95 hot air and that some of these pockets will not be raised to a temperature sufficiently high to kill the nearby bacteria and spores. In order to heat the air in the pockets sufficiently to kill the bacteria and spores, we 100 have, when the illustrated apparatus is employed, removed the pipes I P and E P and have unbolted the door Y and closed the main door H. A pump or other compressing device connected to pipe Z' is then set in operation and air is pumped through the heater Z and by way of pipe Z' into the sterilizer. This is continued until the air in the sterilizer reaches a pressure of, for instance, fifteen pounds per square inch and its temperature is, say, 250° Fahrenheit. The pressure and temperature are preferably then maintained for a period of, say, thirty minutes, or until the operator is satisfied that all of the air within the sterilizer and between the 110 leaves of tobacco has reached a temperature assuring the destruction of the bacteria and spores. The supply of hot air is then cut off and the door H unbolted.

Instead of pumping the hot air into the sterilizer for the purpose of heating the air in the pockets we may first remove all, or nearly all, of the air from the sterilizer, thereby causing a vacuum and then allowing hot air at atmospheric pressure to enter into the chamber. This will assure the entrance of the hot air into any pockets.

The practice of the two steps—first, thoroughly drying the tobacco before subjecting the same to a sterilizing action, and, second,

thoroughly sterilizing the same by subjecting all parts of the same to the heat of hot air—results in the production of dry sterilized tobacco with its structure and quality uninjured, and while awaiting the addition of tobacco bacteria thereto there will be no tendency of the leaves to rot or spoil. The sterilized tobacco may then be set aside to be again subjected to a second sterilization, if desired, in case undeveloped spores existing on the tobacco have not been destroyed.

In carrying out the process it is desirable to prevent the heat from escaping through the walls of the sterilizer, and in the form of apparatus illustrated this is accomplished by maintaining the steam-jacket F full of steam, and the heat of the steam also contributes to the heating of the air circulated or pumped into the sterilizer. The keeping of the inner walls of the sterilizer heated also prevents the accumulation or precipitation of moisture therein. This is especially advantageous when the apparatus is employed to sterilize tobacco to be used for cigar-wrappers, which if steam or precipitated moisture were used would "spot" or "pit" the tobacco, decreasing its commercial value.

The tobacco having been thoroughly sterilized, and after cooling, is inoculated with bacteria obtained from tobacco the flavor of which is to be reproduced or with cultures of such bacteria. We prefer that the inoculation be produced by dipping the leaves into a culture, or the inoculation may be effected by spraying onto or otherwise adding to the tobacco a culture containing bacteria of the desired kind or kinds. For the purpose of producing the desired cultures bacteria are isolated from tobacco (say Havana tobacco) and are grown in a suitable medium—a water extract of ripe tobacco-leaves, for instance—until they reach a sufficient number, say one hundred million to the pound. In order to ascertain whether the cultures are of the desired strength or of the proper kind, small trial lots of tobacco may be inoculated and quickly fermented and the flavor tested by smoking or otherwise. The spraying of the cultures may be done by thoroughly shaking the tobacco-leaves before a jet or stream into which the cultures are introduced, preferably at a right angle to the jet or stream, or bacteria and powdered licorice or other material suitable for bacteria food may be added. If desired, spraying machinery may be used, and the cultures added may be dry or liquid. After inoculation the tobacco may be further moistened, if desired, and then bulked down or handled in any desirable way under conditions which will allow the bacteria to grow or fermentation to ensue.

The subjection of tobacco to the action of hot air for the purpose of sterilizing the tobacco was not an obvious thing prior to our invention. It was known that when steril-

ization by hot air was attempted the temperature of the air would necessarily be very high (higher than that of steam) and that the articles undergoing sterilization would have to be treated for a longer time than when steam was employed. Such a process employing a long-continued high temperature was believed to be useful only when tough hard materials of the same structure throughout—for instance, earthenware, horsehair, &c.— were to be sterilized. Tobacco-leaves, however, have hard and tough parts—the stems and fibers—and very tender soft parts, and because of the great differences between the parts the hot-air process of sterilization would be considered inapplicable to tobacco, inasmuch as the leaves would be injured and for wrapper purposes rendered useless. Our experiments have also demonstrated that when it is attempted to sterilize tobacco by subjecting it to hot air there are several practical difficulties. These have been overcome by our new process. The first of these—the tendency of the tender parts of the leaf to become charred when the high temperature is employed—we have overcome by causing the hot air to be circulated within the chamber and through the mass of tobacco, by which expedient we found the time of treatment of the tobacco was materially reduced with decreased liability to injure the tobacco. A second difficulty was that pockets between leaves retained air and that this prevented thorough sterilization at or near the pockets unless the treatment was so long continued as to injure the tobacco. As hereinbefore described, this was overcome by subjecting the tobacco to the action of hot air under pressure after circulating hot air through the sterilizer.

Among the advantages due to using the hot-air modification of our invention are the following: The leaves are not discolored, spotted, or pitted and do not lose their gloss and when moistened for use "take water" well and are not left harsh, dry, or stiff, but retain their flexibility and elasticity.

We do not herein claim the process of sterilizing tobacco, then adding characterizing bacteria or cultures and bacterial food to the tobacco, and finally fermenting the same.

The apparatus described herein and illustrated in the accompanying drawings is one which we have found to be practical. Any other apparatus which will accomplish the results aimed at may be employed without departing from our invention.

What we claim, and desire to secure, is—

1. The process of treatment of tobacco, consisting in, first, completely drying the leaves of the tobacco, and then sterilizing the tobacco by subjecting the same to the action of hot air under pressure, substantially as and for the purpose described.

2. The process of treatment of tobacco,

consisting in, first, completely drying the leaves of the tobacco, and then sterilizing the tobacco by subjecting the same to the action of a sterilizing medium, substantially as and for the purpose described.

3. The process of treatment of tobacco, consisting in sterilizing the tobacco by subjecting the same to the action of hot air in artificial circulation, and in direct contact with the tobacco, substantially as and for the purpose described.

4. The process of treatment of tobacco, consisting in sterilizing the tobacco by sub-

jecting the same to the action of hot air in circulation, and subsequently to the action of hot air under pressure greater than that of the atmosphere, substantially as and for the purpose described.

In witness whereof we have hereunto signed our names this 19th day of March, 1900.

ALFRED C. BEDORTHA.
GEORGE Q. BEDORTHA.

In presence of—

FRED P. HOLT,
FRANK C. SUMNER.
